[57] CLAIM

The ornamental design for a paper and document handling apparatus, as shown and described.

DESCRIPTION

FIG. 1 is a front perspective view of the top, front and right-hand side of a paper and document handling apparatus showing my new design;

FIG. 2 is an enlarged top plan view thereof;

FIG. 3 is an enlarged rear elevational view thereof;

FIG. 4 is an enlarged left-hand side elevational view thereof;

FIG. 5 is an enlarged front elevational view thereof;

FIG. 6 is an enlarged bottom plan view thereof.

The right-hand side of the apparatus is substantially identical to the left-hand side thereof as shown in FIG. 4.
